UNITED STATES PATENT OFFICE.

WILLIAM W. LEACH, OF MANSFIELD, OHIO, ASSIGNOR OF ONE-HALF TO WILLIAM H. DIXON, OF MANSFIELD, OHIO.

FURNACE.

1,308,987.

Specification of Letters Patent.

Patented July 8, 1919.

Application filed February 13, 1919. Serial No. 276,785.

To all whom it may concern:

Be it known that I, WILLIAM W. LEACH, a citizen of the United States of America, residing at Mansfield, in the county of 6 Richland and State of Ohio, have invented certain new and useful Improvements in Furnaces, of which the following is a specification.

This invention relates to sheet metal heating furnaces and is especially adapted for 10 use in burning powdered coal.

The use in sheet metal rolling mills of the conventional type of furnace for heating sheet metal has many disadvantages which 15 are especially aggravated when powdered fuel is burned in operating same for heating purposes. The present invention aims to overcome and eliminate to a large extent the disadvantages referred to which are well known to those skilled in the art of operating sheet metal furnaces.

The objects, therefore, of the present invention are to construct and build a furnace for heating sheet metal that will continuously and automatically keep and maintain 20 the furnace and piles of sheet metal clean and free from the usual debris and dust which is incident to the use and operation of the conventional type of furnace; to maintain uniform heat throughout the chamber 25 of the furnace so as to heat the sheets more uniformly and evenly throughout the bulk and area of same; to provide a cross connecting flue which is in communication with 30 the stack for the purpose of collecting and drawing the dust and other debris into said flue from the furnace at predetermined points across the entire width of the furnace; to provide ready, free and easy access 35 to the fire box and interior of the furnace for the purpose of repairing same and to provide means of removing the slag, or other debris from the fire box without disturbing, removing, adjusting, or opening the 40 fire box closure or door; to provide means of injecting steam or air, into the furnace to clean the roof thereof from dust or other debris incident or due to the combustion of the fuel; to provide a novel fire box that aids 45 materially in conducting slag or other in-combustible residue of the products of combustion to a point easily accessible to the operator of the furnace thereby permitting the removal of the slag and debris with ease 50 and convenience during the operation of the 55

furnace and burning of the fuel; to provide means of regulating the draft of the furnace and cleaning flues thereof.

These and other objects are attained by building and constructing a furnace as 60 shown in the drawings in which:

Figure 1 shows a mediate longitudinal section of the furnace.

Fig. 2 shows a cross section of the furnace taken on the line 6--6 of Fig. 1. 65

Fig. 3 a top plan view of the furnace showing portions of the top broken away to more clearly show its construction.

Fig. 4 is a rear elevation of the furnace.

Fig. 5 a diagrammatic side view of the 70 furnace showing the position of the flues with relation to the chamber and fire box of the furnace and stack.

Fig. 6 is a front view of Fig. 5 with a portion thereof broken away to show a section 75 on the line 2--2 of Fig. 5.

In constructing and building a furnace to carry out the objects sought to be obtained by the invention, side walls 1 and 2 are provided and built to connect with a front wall 80 3. The rear walls 4 and 5 of the furnace converge from the side walls to form a substantially V shaped structure leaving an opening between the ends which is closed by a hinged door 6 secured to a plate 26. 85 The door carries a conventional type of burner 7 for use in burning powdered coal the coal being conducted into the fire box 8 from any source of supply through the medium of air pressure or the like. A roof 90 9 which is formed preferably of sloping contour is provided and adapted to rest upon and be supported by the side, front and rear walls of the furnace thereby forming a chamber 10 into which the sheet metal is 95 placed and supported on the corrugated bottom 11 preparatory to heating same for the purpose intended.

The furnace chamber and bottom is preferably divided by a partition wall 12 which is built in the center of the chamber running from the front wall 3 rearwardly to a predetermined point adjacent to the rear walls of the furnace and it intersects at said point with bridge walls 13 and 14. The partition 105 and bridge walls do not extend to the roof of the furnace so that both sides of the chamber that are divided by the partition wall 12 are always in communication with each other. The bridge walls are preferably 110.

provided with tapered projecting portions 15 and 16 which serve as deflectors. The bottom 17 of the fire box is connected with the bridge walls and inclines or slopes downwardly and is connected or attached to the front ends of the rear walls 4 and 5 and the bridge walls.

The above described construction provides as shown in Figs. 1 and 3 a fire box having a downwardly inclined or sloped bottom, with the rear walls of the furnace diverging toward the side walls of the furnace thereby forming a fire box that gradually enlarges toward the furnace chamber and which merges into the full width thereof as shown in Fig. 3. Preferably at a point where the rear walls 4 and 5 merge into the side walls 1 and 2 and adjacent to the bottom of the furnace, a flue 18 is provided running from one side of the furnace to the other and it is in communication with flues 19 and 20 which in turn communicate with a stack 21. Flues 22 and 23 are provided in the side walls 1 and 2 of the furnace and preferably inclined downwardly toward the front and bottom 11 of the furnace. The openings 24 provide communication between the flues and fire box 8. The flues 22 and 23 also communicate with flues 25 which are open to the air to induce a natural draft or permit a forced draft to be applied thereto. The flues 25 formed in the front walls of the furnace as shown in Fig. 3 also communicate with the flues 22, 23 and 25 as shown in Fig. 3.

The ends of the rear walls 4 and 5 of the furnace have the apertured plate 26 attached thereto which is provided with openings 27 and 28 which align with the open ends 40 of the flues 25 thereby admitting atmospheric air into all the connecting flues and also providing means of applying steam or air pipe connections to create a forced draft if desired through the flues for a purpose 45 which will be described particularly hereinafter.

In order to regulate the forced or natural draft of the flues, adjustable dampers 29 are provided to close or open flues 19 and 20 more or less. To the plate 26 the door 6 is hinged in a conventional manner and it carries the conventional type of burner 7 for burning powdered coal or the like. This door and plate provide a closure for a part 55 of the opening formed between the rear walls 4 and 5 of the furnace and also provides means whereby ready and convenient access can be had to the fire box by simply swinging the door on its hinges. The inclined bottom 17 of the fire box is constructed so that its end will be positioned below the bottom of the door 6 leaving an auxiliary opening 32 which is normally closed by a hinged door 34 as shown in Figs. 60 1 and 4. This arrangement provides a

means of removing the slag or other debris that accumulates in the fire box 8 without opening or removing the door 6.

The inclined bottom 17 of the fire box provides means of permitting the slag or other debris to fall by gravity toward the opening 32. When the accumulation of slag or other debris is deposited or formed in the fire box and it is desired to remove the same therefrom the operator opens the door 34 and removes the slag or other debris without disturbing or opening the door 30 which carries the burner 7 or in any manner interfering with the operation of the furnace.

It will be observed that this cleaning process can be performed during the operation of the furnace and burning of the fuel in the fire box with ease and convenience. When, however, it is desired to repair the fire box or interior of the furnace the door covering the openings 33 and the door covering the opening 32 can both be swung on their hinges from the openings thereby permitting easy and convenient access through the medium of the combined openings to the interior of the furnace for any purpose desired.

To provide means for cleaning the roof 36 of the furnace steam or air pipes 37 and 38 are nested in chambers 39 and 40 formed in the side walls of the furnace, and they are provided with a series of jets 41 arranged at predetermined points which align with openings 42 communicating with the chamber 10 of the furnace. The openings are inclined upward toward the roof 36 of the furnace as shown in Fig. 2 and when it is desired to clean the roof of the furnace a steam or air connection 43 is made with the pipes 36 and 37 from any source of supply, spraying the steam or forcing the air against different points of the roof of the furnace, thereby cleaning same of the debris and dust.

The jets 41 are arranged and disposed in the side walls preferably in parallel but in offset relation to each other. The cross horizontal flue 18 is brought into communication with the chamber 10 by a series of openings 44 arranged at predetermined points across the entire width of the furnace.

The mouth of the furnace 45 is closed by the usual conventional sliding door 46. Attention is called to the fact that openings are provided throughout the furnace that intersect with the flues at various points for cleaning purposes so that the flues can be cleaned during the operation of the furnace at any time desired. The flue openings are closed by conventional hinged doors such as shown at 47 and 48. The front wall of the furnace is provided with openings 49 which intersect with the flues and communicate with the chamber 10.

Attention is called to the fact that the sides of the furnace with respect to flue arrangement, etc., are duplicates of each other.

The furnace shown in the drawings is especially designed and adapted for burning powdered coal or gaseous fuel. In material alterations may be made in the construction without parting from the spirit of the invention.

- 10 The operation of the furnace is as follows: Powdered coal is conducted by air pressure into the fire box 8 where it is ignited and burned in the usual manner. The products of combustion pass from the fire box 8 into the combustion chamber 10 toward the bridge walls 13 and 14 and are deflected by the projecting portions 15 and 16 toward the front; thence they are returned toward the rear portion of the chamber passing through the openings 44 into the horizontal flue 18; thence through the flues 19 and 20 to the stack 21. A portion of the products of combustion is diverted from the chamber passing through the openings 24 provided in each side of the fire box into the flues 22, 23 and 25 and through the openings 49, into the chamber 10; thence through the openings 44 into the flue 18 where the heavier particles of dust and debris lodge and collect, and the volatile products of combustion pass out through the flues 19 and 20 into the stack 21 to the atmosphere.

The natural draft from the stack naturally tends to create a suction or draft in the chamber drawing the dust or other debris from the chamber through the openings 44 into the flue 18 from the main chamber 10. The natural draft of the stack also at the same time creates a suction or draft through the openings 27 and 28 and flues 22, 23 and 25; thence through the openings 49 into the chamber and out through the openings 44 through the flue 18 to the stack 21.

In order to provide for greater efficiency in the operation of and the cleaning of the furnace it is preferable to create a forced draft through the medium of steam or the like by connection from any source of supply to the flues and applying same at the openings 27 and 28 which are in communication with the flues 22, 23, 25 and 25'. The suction or draft created by the air or steam is such that there is a continuous draft through the furnace tending to draw and suck all dust, debris and other particles of dirt or foreign substance toward and through the openings 44 into the flue 18 cleaning the metal and drawing the dust, debris and other foreign substance from the heated metal and chamber of the furnace into the flue 18 thereby preventing same from being absorbed into and mixing with the metal causing impure and defective metal.

Attention is called to the fact that because the outlet of the flues and the stack are

located in the rear of the furnace that advantage is taken of the return or doubling back of the heat from the front of the furnace to the rear of the furnace at which point it escapes into the stack, instead of permitting it as in the conventional type of furnace to escape out through the flues to a stack located in the front of the furnace.

It will be obvious to those skilled in the art that the furnace shown and described in the drawings can be used with immaterial alterations to operate successfully with fuel other than powdered coal and gaseous fuel.

I claim:

1. In a furnace, a fire box, side, front and rear walls forming a main chamber, the side walls of the chamber being provided with flues opening into the fire box, open to the atmosphere, and extending from the fire box through the side walls and front walls to communicate with said chamber from the front wall.

2. In a furnace, a fire box, side, front and rear walls forming a main chamber, the side walls of the chamber being provided with flues opening into the fire box, open to the atmosphere, and extending from the fire box through the side walls and front walls to communicate with said chamber from the front wall, and a cross flue arranged adjacent to the rear wall of the chamber and in communication with the chamber.

3. In a furnace, a fire box, side, front, and rear walls forming a main chamber, the side walls of the chamber being provided with flues opening into the fire box, open to the atmosphere, and extending from the fire box through the side walls and front walls to communicate with said chamber from the front wall, a cross flue arranged adjacent to the rear wall of the chamber and in communication with the chamber, a stack and means of connecting the cross flue to the stack and chamber.

4. In a furnace, a fire box, side, front, and rear walls forming a chamber and provided with communicating flues opening at one end to the atmosphere and at the other end into the chamber and fire box, a stack, a roof supported by said walls, a cross flue arranged adjacent to the bottom and in close proximity to the rear walls of the furnace and provided with a series of openings which communicate with the chamber thereby providing means for creating a suction toward the rear portion of the chamber into the cross flue depositing the heavier particles of products of combustion in the cross flue and permitting the volatile products to escape through the stack.

5. In a furnace, a fire box, side, front and rear walls forming a chamber and provided with communicating flues opening at one end to the atmosphere and at the other end into the chamber, said flues being also in com-

munication with the fire box, a roof supported by said walls, a cross flue arranged adjacent to the bottom and rear end of the chamber of the furnace and provided with a series of openings which communicate with the chamber, a stack, flues in communication with the cross flue, stack and chamber.

6. In a furnace, side, front and rear walls forming a chamber and provided with communicating flues open at one end to the atmosphere and at the other end to the chamber, a roof supported by said walls, a cross flue arranged adjacent to the bottom of the furnace and provided with a series of openings which communicate with the chamber, a stack, flues connected to the cross flue and stack and in communication with both, and means arranged and nested in chambers formed in and along the side walls of the furnace to afford facilities for cleaning the roof of the furnace.

7. In a furnace, front, rear and side walls, and a roof forming a chamber, said rear walls also forming a V shaped fire box, leaving an opening at the ends, an inclined bottom arranged in the fire box, a plate attached to the ends of the rear walls having an opening provided therein, a fire box door hinged to said plate and adapted to close said opening, said rear walls also being provided with an auxiliary opening beneath the fire box door to provide means of removing the slag and other debris from the fire box, a door hinged to the aforementioned plate to overlap the fire box door and adapted to close the auxiliary openings.

8. In a furnace, front, rear and side walls, and a roof forming a chamber, said rear walls also forming a V shaped fire box, leaving an opening at the ends, an inclined bottom arranged in the fire box, a plate attached to the ends of the rear walls having an opening provided therein, a fire box door hinged to said plate and adapted to close said opening, said rear walls also being provided with an auxiliary opening beneath the fire box door to provide means of removing the slag and other debris from the fire box, a door hinged to the aforementioned plate to overlap the fire box door and adapted to close the auxiliary openings, and means to clean the duct and other debris from the roof.

9. In a furnace provided with a chamber, said furnace also being provided with side flues open at one end to the atmosphere to permit of a forced draft being applied thereto and having the opposite ends thereof communicating with the chamber, an open fire box provided on the furnace and in communication with said side flues, closure means hinged to the furnace to open and close the fire box opening.

10. In a furnace provided with a chamber, said furnace also being provided with flues open at one end to the atmosphere to permit

of a forced draft being applied thereto and having the opposite ends thereof communicating with the chamber, a fire box provided on the furnace and in communication with said flues, means to open and close the fire box, and independent auxiliary means also provided on the furnace to permit free and easy access to the bottom of the fire box to remove the slag or other debris formed or deposited therein from the incombustible products of combustion.

11. In a furnace provided with a chamber, said furnace also being provided with flues open at one end to the atmosphere to permit of a forced draft being applied thereto and having the opposite ends thereof communicating with the chamber, a fire box provided on the furnace and in communication with said flues, means to open and close the fire box, independent auxiliary means also provided on the furnace to permit free and easy access to the bottom of the fire box to remove the slag or other debris formed or deposited therein from the incombustible products of combustion, and means to clean the roof of the furnace.

12. In a furnace provided with a chamber, said furnace also being provided with flues open at one end to the atmosphere to permit of a forced draft being applied thereto and having the opposite ends thereof communicating with the chamber, a fire box provided on the furnace and in communication with said flues, means to open and close the fire box, independent auxiliary means also provided on the furnace to permit free and easy access to the bottom of the fire box to remove the slag or other debris formed or deposited therein from the incombustible products of combustion, and means to clean the roof of the furnace.

13. In a furnace comprising side, front and rear walls, the rear walls being provided with flues which communicate with flues provided in the side and front walls, a roof for said walls, a fire box having openings communicating with said flues, and also provided with a sloping bottom.

14. In a furnace comprising side, front and rear walls, the rear walls being provided with flues which communicate with flues provided in the side and front walls, a roof for said walls, a fire box having openings communicating with said flues and also provided with a sloping bottom, a cross horizontal flue arranged adjacent to the bottom and rear of the furnace, a stack, and flues connected to the stack and cross horizontal flue.

15. In a furnace comprising side, front and rear walls, the rear walls being pro-

- vided with flues which communicate with flues provided in the side and front walls, a roof for said walls, a fire box having openings communicating with said flues and also provided with a sloping bottom and rear of the furnace, a stack, flues connected to the stack and cross horizontal flue, and means to clean the roof of the furnace.
16. In a furnace comprising walls forming a chamber, the rear walls of which are arranged to converge from the side walls of the furnace forming a substantially V shaped fire box and leaving an opening between them, a bottom fitted to the fire box to incline toward the bottom of the furnace and means to close the fire box opening.
17. In a furnace comprising walls forming a chamber, the rear walls of which are arranged to converge from the side walls of the furnace leaving an opening between them to form the side walls of a fire box, a bottom fitted to the fire box to incline toward the bottom of the furnace, and flues provided in the walls of the furnace and in communication with the fire box, atmosphere, and chamber of the furnace.
18. In a furnace comprising walls forming a chamber, the rear walls of which are arranged to converge from the side walls of the furnace leaving an opening between them to form the side walls of a fire box, a bottom fitted to the fire box to incline toward the bottom of the furnace, flues provided in the walls of the furnace and in communication with the fire box, atmosphere, and chamber of the furnace and means to close the opening between the side walls of the fire box.
19. In a furnace, comprising walls forming a chamber, the rear walls of which are arranged to converge from the side walls of the furnace leaving an opening between them to form a fire box, a bottom fitted to the fire box to incline toward the bottom of the furnace, flues provided in the walls of the furnace and in communication with the fire box, atmosphere, and chamber of the furnace, means to close the opening between the side walls forming the fire box, and means independent of the closing means of the fire box to permit access to the fire box to remove the slag deposited therein from the products of combustion.
20. In a furnace, comprising walls forming a chamber, the rear walls of which are arranged to converge from the side walls of the furnace leaving an opening between them to form a fire box, a bottom fitted to the fire box to incline toward the bottom of the furnace, flues provided in the walls of the furnace and in communication with the fire box, atmosphere, and chamber of the furnace, means to close the opening between the side walls forming the fire box, means independent of the closing means of the fire box to permit access to the fire box to remove the slag deposited therein from the products of combustion.
21. In a furnace, comprising walls forming a chamber, the rear walls of which are arranged to converge from the side walls of the furnace leaving an opening between them to form a fire box, a bottom fitted to the fire box to incline toward the bottom of the furnace, flues provided in the walls of the furnace and in communication with the fire box, atmosphere, and chamber of the furnace, means to close the opening between the side walls forming the fire box, means independent of the closing means of the fire box to permit access to the fire box to remove the slag deposited therein from the products of combustion, means to clean the roof of the furnace, a stack, a cross horizontal flue and flues connecting the horizontal flue and stack.
22. The combination in a furnace of an open front fire box provided with a sloping bottom, means of closing the opening of the fire box, the walls of the furnace being provided with flues which communicate with the fire box and chamber of the furnace.
23. The combination in a furnace of an open front fire box provided with a sloping bottom, means of closing the opening of the fire box, the walls of the furnace being provided with flues which communicate with the fire box and chamber of the furnace, a horizontal flue arranged adjacent to the bottom of the furnace, a stack, and flues in communication with the stack and horizontal flue.
24. The combination in a furnace of an open front fire box provided with a sloping bottom, means of closing the opening of the fire box, the walls of the furnace being provided with flues which communicate with the fire box and chamber of the furnace, a horizontal flue arranged adjacent to the bottom of the furnace, a stack, flues in communication with the stack and horizontal flue, and means to apply a forced draft in the flues formed in the walls of the furnace.
25. The combination in a furnace of an open front fire box provided with a sloping bottom, means of closing the opening of the fire box, the walls of the furnace being provided with flues which communicate with the fire box and chamber of the furnace, a horizontal flue arranged adjacent to the bottom of the furnace, a stack, flues in communication with the stack and horizontal flue, means to apply a forced draft in the flues formed in the walls of the furnace and means to clean the roof of the furnace.
26. In a furnace, comprising a chamber and a fire box, means of injecting powdered fuel into said fire box and the products of combustion into the chamber, and means

- comprising flues which are in communication with the fire box and the front of the chamber for creating a suction in the chamber by natural or forced draft to suck and collect the heavier products of combustion into a receptacle provided at the rear of the chamber.
27. In a furnace, comprising a chamber and a fire box, means of injecting powdered fuel into said fire box and the products of combustion into the chamber, means comprising flues which are in communication with the fire box and the front of the chamber for creating a suction in the chamber by natural or forced draft to suck and collect the heavier products of combustion into a receptacle provided at the rear of the chamber, and means to conduct the volatile products of combustion to the atmosphere from said receptacle.
28. In a furnace, comprising a chamber and a fire box, means of injecting powdered fuel into said fire box and the products of combustion into the chamber, means comprising flues which are in communication with the fire box and the front of the chamber for creating a suction in the chamber by natural or forced draft to suck and collect the heavier products of combustion into a receptacle provided at the rear of the chamber, means to conduct the volatile products of combustion to the atmosphere from said receptacle, and means to clean the top of the furnace.
29. In a furnace, comprising a chamber and a fire box, means of injecting powdered fuel into said fire box and the products of combustion into the chamber, means comprising flues which are in communication with the fire box and the front of the chamber for creating a suction in the chamber by natural or forced draft to suck and collect the heavier products of combustion into a receptacle provided at the rear of the chamber, means to conduct the volatile products of combustion to the atmosphere from said receptacle, means to clean the top of the furnace, and flues provided in the furnace and arranged to communicate with the fire box and front of the chamber.
30. In a furnace, comprising a chamber and a fire box, means of injecting powdered fuel into said fire box and the products of combustion into the chamber, means comprising flues which are in communication with the fire box and the front of the chamber for creating a suction in the chamber by natural or forced draft to suck and collect the heavier products of combustion into a receptacle provided at the rear of the chamber.
31. In a furnace, comprising a chamber and a fire box, means of injecting powdered fuel into said fire box and the products of combustion into the chamber, means comprising flues which are in communication with the fire box and the front of the chamber for creating a suction in the chamber by natural or forced draft to suck and collect the heavier products of combustion into a receptacle provided at the rear of the chamber.
32. In a furnace, comprising side and front walls forming a chamber, in combination with rear converging walls which are spaced apart at their free ends to form a fire box; in combination with a sloping and converging bottom which is attached to the rear walls and a closure means which is adapted to close the space between the ends of the side walls or permit access to the fire box if desired.
33. In a furnace comprising side and front walls in combination with rear converging walls which are spaced apart at their free ends to provide an opening, a sloping bottom secured to said rear walls which with the rear walls provide a fire box, an apertured plate secured to the free ends of the rear walls, and closure means hinged to said plate to close or open one of the openings.
34. In a furnace comprising side and front walls in combination with rear converging walls which are spaced apart at their free ends to provide an opening, a sloping bottom secured to said rear walls which with the rear walls provide a fire box, an apertured plate secured to the free ends of the rear walls, closure means hinged to said plate to close or open one of the openings, and a burner secured to said closure means.
35. In a furnace comprising side and front walls in combination with rear converging walls which are spaced apart at their free ends to provide an opening, a sloping bottom secured to said rear walls which with the rear walls provide a fire box, an apertured plate secured to the free ends of the rear walls, closure means hinged to said plate to close or open one of the openings, a burner secured to said closure means, and a second closure means hinged to said plate and located below the first named closure means to permit access to the fire box without affecting the first mentioned closure means.
36. In a furnace, comprising a chamber and a fire box, flues substantially surrounding the furnace having communication with the atmosphere, fire box and chamber in combination with a cross horizontal flue which is in communication with the chamber and atmosphere.
37. In a furnace, comprising a chamber and a fire box, flues substantially surround-

- ing the furnace having communication with the atmosphere, fire box and chamber, whereby means are provided to inject a forced draft into the flues and chamber in combination with a cross horizontal flue which is in communication with the chamber and atmosphere.
38. In a furnace comprising a chamber and a fire box, flues substantially surrounding the furnace having communication with the atmosphere, fire box and chamber, means to inject a forced draft into the flues and chamber, and means to create a suction in the chamber to withdraw therefrom the unburned products of combustion, and deposit same in a receptacle.
39. In a furnace, a fire box formed of converging walls which are spaced apart at their free ends in combination with a bottom which is attached to the converging walls and a closure means which is adapted to close the space between the ends of the side walls or permit access to the fire box if desired.
40. In a furnace, a fire box formed of converging walls which are spaced apart at their free ends in combination with a bot-
- tom which is attached to the converging walls, a plate having an opening substantially of a size equal to the space between the free ends of the wall, and a hinged mounted means adapted to close said space partially or completely.
41. In a furnace, a fire box, a chamber in communication therewith, flues in communication with the fire box, atmosphere and chamber, whereby a suction is created in the chamber at the rear thereof, means to carry off the uncombustible products of combustion to the atmosphere, and means operable therewith to clean the roof of the chamber.
42. In a furnace, a fire box, a chamber in communication therewith, flues in communication with the fire box, atmosphere and chamber, means whereby a suction is created in the chamber, means to carry off the uncombustible products of combustion to the atmosphere, means to clean the roof of the chamber, and a partition wall dividing the chamber, a bridge wall intersecting therewith and connected to the fire box.

In testimony whereof I affix my signature.
WILLIAM W. LEACH.
